Term of patent 14 years

(Cl. D58—17)

FIG. 1 is a side elevational view of a packaging cup or similar article showing my new design;

FIG. 2 is an enlarged fragmentary view of a portion of FIG. 1;

FIG. 3 is a developed plan view of the ornamentation;

FIG. 4 is a cross sectional view taken along the line 4—4 in FIG. 2;

FIG. 5 is a cross sectional view taken along the line 5—5 in FIG. 2.

The characteristic feature of my design resides in the combination on the cup disclosed of the specific ribbed pattern disposed on both the inner and outer faces, said ribs terminating substantially at a bottom foot and at a plain band at the top somewhat below the rolled rim all as shown.

This application is a continuation-in-part of my co-pending application Serial No. D. 64,986, filed May 1, 1961, now abandoned.

I claim:

The ornamental design for a packaging cup or similar article, substantially as shown and described.
